(57) **CLAIM**

An ornamental design for a growler bottle, as shown and described.

DESCRIPTION

FIG. 1 is a front perspective view of a first embodiment of a growler bottle showing our new design;

FIG. 2 is a front elevational view thereof;

FIG. 3 is a rear elevational thereof;

FIG. 4 is a left-side elevational view thereof;

FIG. 5 is a right-side elevational view thereof;

FIG. 6 is a top view thereof;

FIG. 7 is a bottom view thereof;

FIG. 8 is a front perspective view of a second embodiment of a growler bottle;

FIG. 9 is a front elevational view thereof;

FIG. 10 is a rear elevational view thereof;

FIG. 11 is a left-side elevational view thereof;

FIG. 12 is a right-side elevational view thereof;

FIG. 13 is a top view thereof; and,

FIG. 14 is a bottom view thereof.

The broken lines in the drawing depict portions of the growler bottle that form no part of the claimed design.

1 Claim, 12 Drawing Sheets
